Title:

UNITED STATES PATENT OFFICE

HORACE H. HUBER, OF INDIANAPOLIS, INDIANA, ASSIGNOR TO CHAMPION
CARBURETOR, A TRUST

CARBURETOR

Application filed March 25, 1932. Serial No. 601,187.

In the operation of an automobile two requisites are required of the carburetor, economy of fuel and maximum amount of power.

5 It has been found that in obtaining the maximum amount of power such as is necessary when accelerating or running with wide open throttle, it is necessary to use a richer mixture than when operating under road 10 loads or steady running on level roads with part throttle, at which times it is necessary to use a very lean mixture for economy sake, and at the same time maintain a good combustible ratio.

15 In order to accomplish this result, it is one of the objects of the present invention to provide an automatically controlled device to regulate the mixture ratio, independent of the throttle, to meet the demands, and by means 20 of which these various mixture ratios will be obtained accurately and automatically in the device through the medium of the use of the differences of vacuum that occur on the engine or suction side of the throttle valve.

25 To the attainment of these ends and the accomplishment of other new and useful objects as will appear, the invention consists in the features of novelty in substantially the construction, combination and arrangement 30 of the several parts hereinafter more fully described and claimed and shown in the accompanying drawings illustrating this invention, and in which

35 Figure 1 is a vertical sectional view of a carburetor of this character constructed in accordance with the principles of this invention.

40 Figure 2 is a detail sectional view of an accelerating pump and fuel mixture control means, with the parts in a position different from that shown in Figure 1.

Figure 3 is a view similar to Figure 2, with the parts in a different position.

45 Figure 4 is a sectional view taken on line 4—4, Figure 1.

Figure 5 is a detail sectional view taken on line 5—5, Figure 1, on a larger scale.

Figure 6 is a detail sectional view taken on line 6—6, Figure 1.

50 Figure 7 is a detail vertical sectional view

of a portion of the fuel nozzle on an enlarged scale and with parts omitted.

Figure 8 is a detail sectional view taken on line 8—8, Figure 4, on an enlarged scale and with parts omitted.

55

Figure 9 is a detail, vertical, sectional view of the venturi.

Referring more particularly to the drawings the numeral 10 designates generally a carburetor casing having an air supply inlet 11 and a discharge outlet 12 for delivering the fuel to the engine, and the carburetor may be secured in position by means of the usual flange 13 which is attached to the manifold of the engine. A throttle valve 14 controls the discharge of fuel from the mixing chamber through the outlet 12.

65

Arranged within the casing is a horizontal partition 15 having an opening 16 therethrough for admission of air, and this opening is controlled by means of a valve 17 pivotally mounted as at 18, and 19 designates a spring, one end of which is connected with the valve 17 and tends normally to close the same. The partition 15 is provided with an opening therethrough in which the base 20 of a sleeve 21 is seated and the sleeve 21 is open at its top and bottom, the base being provided with a groove 22 which opens through the periphery thereof and is closed 80 by the wall of the opening in which the base of the sleeve is seated.

70

An opening 23 is provided in the bottom of the carburetor to form a shoulder 24 and a nozzle member 25 having a reduced portion 26 to form a shoulder 27 is inserted in the opening 23, so that the shoulder 27 will abut the shoulder 24 and the nozzle element is held in position by means of suitable fastening screws 28. The upper extremity of the portion 26 is tapered as at 29, and an opening 30 extends through the bottom of the nozzle element and is provided with a reduced upper portion 31 having branches 32 which lead through the tapered portion 29. Seated within the recess 30 is an ejector nozzle 33 held in position preferably by means of suitable threads engaging in the threaded portion of the wall of the recess 30, and the upper extremity of this element 33 is reduced 100

95

as at 34, to an external diameter considerably less than the internal diameter of the recess 30, the extremity 35 of the element 34 terminating considerably short of the reduced opening 31 of the recess.

A passage 36 extends through the extremity 35 of the element 34 and terminates short of the bottom of the element 33 and has a lateral opening 37 extending through the 10 wall of the element to communicate with the passage 38 in the member 25 and which passage 38 has communication with a circumferential recess 39 opening through the periphery of the element 25, for a purpose 15 to be set forth.

A cap member 40 telescopes over the tapered extremity 29 of the element 25 and is provided with grooves 41 opening through the periphery thereof to form air passages, 20 and the cap member is arranged directly below the open bottom of the sleeve 21 so that air currents passing into the casing through the opening 11 will flow through the passages 41 and into the sleeve 21. The passages 41 25 are provided with openings 42 in the bottoms thereof which are adapted to be moved into and out of register with the branch passages 32 of the recess 30, so that fuel passing through the branches 32 will also pass 30 through the openings 42 in the passages 41, when the openings 42 are in register therewith, to supply fuel to be atomized by air currents into the sleeve 21. By the rotation of the cap 40 the outlet openings of the 35 passages 32 will be controlled and the fuel discharged therethrough will thereby be metered.

The tapered extremity of the cap member 40 is spaced from the bottom of the sleeve 40 21 so as to form passages for air currents therebetween. It will be manifest that by the rotation of the cap 40 the discharge of fuel will be controlled. Therefore in order 45 to control automatically the oscillation of the cap member 40 by engine suction the cap 40 is operatively connected with the valve 17. This valve 17 serves as a supplemental air supply valve and is itself opened by engine 50 suction and closed by the spring 19, one end of which, as before stated, is anchored to the valve 17 and the other end is anchored as at 43 preferably to the cap member 40 through the medium of an element 44.

55 Connected with the cap member 40 and projecting laterally therefrom is a T shaped element or bolt 45 which, when in a predetermined position, will pass through a slot 46 in the end 47 of a bar or rod 48, and is then 60 turned transverse to the slot 46 to hold the parts against separation. The other end of the rod 48 is loosely and pivotally connected with the valve 17 by passing through a sleeve 49 and having threaded upon the extremity 65 thereof a nut or collar 50 which rests against

the face of a member 51 through which a bolt 52 passes.

The bolt 52 is secured at one end to the valve 17 and passes through the sleeve or member 51 and has threaded upon it a nut or collar 53. A coiled spring 54 encompasses the rod and one end thereof rests against the sleeve 49, and the other end rests against a pin 55 carried by the rod. The normal tendency of the spring 54 is to hold the nut or collar 50 seated against the sleeve 51.

In order to retard the opening movement of the valve 17, a dash pot construction is preferably provided, consisting of a cylinder 56 in which a piston 57 having an opening 58 therethrough reciprocates. A piston rod 59 is connected preferably by a ball and socket joint 60 with the piston, and the upper end of the piston rod passes through the top of the cylinder 56 and through the valve 17 having a ball 61 which is suitably connected to the end of the rod and is seated in a recess 62, so that when the valve 17 is opened the piston 57 will be raised in the cylinder 56 by the piston rod 59. When the valve 17 closes, however, it is adapted to close independently with respect to the piston 57 and piston rod 59, and a cap or member 63 is provided for closing the open end of the cylinder 56 and is adapted to be moved across the end of the cylinder by the movement of the rod 59 as the valve 17 is opening and closing. A spring 64 may be provided in the cylinder 56 to assist in returning the piston 57.

Liquid is supplied to the cylinder 56 from a reservoir 65 through the medium of a passage 66 which communicates with a circumferential groove 67 in the bottom of the member 25 and opens through the periphery thereof. A passage 68 extends through the body of the base of the nozzle element 25 and forms communication between the groove 67 and the recess 30. A passage 69 is provided in the wall of the carburetor which forms communication with the interior of the cylinder 56 so that fuel from the supply chamber 65 will be supplied to the cylinder 56 through the passage 66, groove 67 and passage 69. At the same time the fuel will be supplied to the recess 30 through the passage 68 which forms the communication between the groove 67 and the recess 30.

A valve 70 controls the inlet opening 11 and this valve is provided with an opening 71 therethrough closed by a member 72, which latter is connected with a spring 73, one end of which is secured as at 74 to the element 72 and the other end as at 75 to the valve 70. With the usual construction of valve when the engine starts the suction would ordinarily be sufficient to flood the carburetor before the valve 70 is opened, and in order to prevent such operation, the member 72 is provided which will be unseated by suction so as to permit enough air to pass through the opening 130

71 to mix with the fuel before the valve 70 is operated.

In order to attain a maximum power by supplying an additional amount of fuel when the suction in the engine drops suddenly, there is provided a cylinder 76 which has communication as at 77 adjacent the bottom thereof with the peripheral groove 39 in the member 25. Arranged with the cylinder 76 is a piston 78 which is hollow, being closed at its bottom and open at the top. The top of the cylinder 76 is closed by a member 79 preferably threaded thereinto and passing through the top 79 are passages 80 which have communication with a circumferential groove 81 closed by the wall of the cylinder. This groove 81 has communication with a passage 82, which in turn has communication with a passage 83 in the wall of the carburetor casing. This passage 83 (see particularly Figure 5) may be formed in any suitable manner preferably by means of a tube 84 molded or cast into the wall of the casing 10 of the carburetor and is provided with an opening 85 in its wall that has communication with the passage 82.

The passage 83 is also provided with another opening 82^a arranged on the engine side of the throttle 14, so that suction, when the valve 14 is closed, will be manifested through the passages 83, 82 and 80 to the interior of the cylinder 76 and piston 78 to draw the latter upwardly against the tension of the spring 86. The inlets of the passages 80 are so arranged that when the piston 78 is in the position shown in Figure 1, the passages will be sealed against the entrance of liquid or air thereinto. The spring 86 rests with one end against the bottom of the piston 78 and contacts with the member or cup shaped element 87 at the other end. A screw 88 passes through the top 79 of the cylinder and is connected to the element 87 so that by adjusting the screw 88, the tension of the spring 86 may be varied. A lock nut 89 is provided for holding the screw against accidental adjustment.

When the suction in the engine overcomes the spring 86, the piston 78 will be held in the position shown in Figure 1. When, however, the suction in the engine decreases sufficiently that the spring 86 will overcome the same, the piston 78 will be lowered, and if this decrease in the suction in the engine is gradual the piston 78 will move down gradually. If, however, the suction is rapid or sudden, the spring 86 will quickly overcome the suction and the piston 78 will be forced downwardly to discharge fuel therefrom through the passage 77 into the peripheral groove 39 of the member 25, thence through the passage 38 into the passage 36 of the injector nozzle 34 and cause fuel to be ejected through the passage 30, passage 31 and branch passages 32 of the passage 31. As soon as the stress of the spring 86 is overcome by the

suction in the engine the piston will be moved back to the position shown in Figure 1.

Fuel is supplied to the cylinder 76 from the fuel supply reservoir 65, through the passage 66, groove 67 in the nozzle element 25, 70 passage 68, recess 30, passage 36 in the injector element 34, thence through passage 38, circumferential groove 39 and passage 77 into the cylinder.

A float 90 is arranged in the reservoir 65 75 for controlling the supply of fuel to the reservoir through the supply opening 91, in any suitable manner.

The passage 83 has communication with the peripheral groove 22 in the base 20 of 80 the sleeve 21, through an opening 92, recess 93, and opening 94 that communicates with the groove 22. A needle valve 95 is arranged to control the opening 94 and is held in position by means of its body portion 96 being threaded into the wall of the casing 10 so that the needle valve will pass through another opening 97 in the wall of the tube 84, which is in alignment with the opening 92. A locking spring 98 may be provided which engages a knurled portion 99 on the needle valve for maintaining the same in its adjusted position. The recess 93 has an opening 100 which communicates with the interior of the carburetor casing and so arranged that air will pass therethrough into the recess 93 to be delivered into the passage 83. Therefore, by adjusting the needle valve 95 to regulate the opening 94, the mixture passing into the passage 83 may be controlled. 100

This passage 83 is provided as a means for maintaining a suction in the cylinder 76 and piston 78 to hold the piston in the position shown in Figure 1, and also as a means for supplying fuel to the suction side of the throttle 14, while the engine is idling, as the suction created in the passage 83 will be manifested through the opening 94, thence in the peripheral groove 22 in the base of the sleeve 21 to draw in atomized fuel which is atomized into the bottom of the sleeve 21 by causing the same to pass through any suitable number of openings 101 (see Figure 1) which pass through the sleeve and the base 20 to form communication with the groove 22. 110

In order to thin out or cause a leaner supply of fuel mixture to be delivered to the engine when the throttle valve 14 is partly opened, as in road load conditions, means are provided for supplying an additional amount of air to the mixture in the mixing chamber, and to that end there is provided a passage 102 which has communication with the interior of the cylinder 76 and also with the carburetor casing beneath the partition 15. 120 Another passage 103 is provided in the casing wall which has communication with the cylinder 76 and also with the interior of the carburetor casing on the other side of the partition 15. The two ports of these passages 125 130

which communicate with the cylinder 76 are preferably located in close proximity to each other and the piston 78 is provided with a circumferentially reduced portion 104, which may be of any desired width, but is of a sufficient width that when the piston 78 is moved into the position shown in Figure 3, the passage formed by the reduced portion 104 with the wall of the cylinder will form communication between the two passages 102 and 103 so as to permit a supply of air to flow into the passage 102, through the passage 104, and thence out of the passage 103 to the other side of the piston to mix with the fuel in the mixing chamber.

During the time that the engine is idling both of the passages 102 and 103 will be closed by the piston 78, as shown in Figure 1.

20 When the engine is running with heavy loads, the piston 78 will assume the position shown in Figure 2, by reason of the fact that the spring 86 overcomes the suction of the engine and moves the piston to this position.

25 In such position both of the passages 102 and 103 will also be closed and the additional supply of air will be cut off.

When, however, the engine is running only under road loads, the suction in the engine 30 will cause the piston 78 to be maintained in the position shown in Figure 3, so that a communication will be formed between the passages 102 and 103 to admit an additional supply of air to the mixing chamber and thereby thin out the fuel supply, and the position in which the piston is held while in a floating position, as shown in Figure 3, will be controlled by the adjustment of the tension upon the spring 86.

40 When these various conditions change the piston 78 will be automatically moved either by the spring 86 when the latter overcomes the engine suction or by the engine suction, when the latter overcomes the stress of the spring 86.

Therefore, the control of the mixture ratio will be such that the mixture will never be richer than is necessary for the maximum power and never leaner than the most efficient 50 economical mixture, regardless of engine speed or engine load; the rich mixtures being used on very heavy loads and the lean mixtures on light loads.

55 This is accomplished by supplying an additional quantity of air to the mixture when needed, controlling the amount thus supplied, and shutting off such additional supply when it is not needed, all being controlled by engine suction, the said additional air supply 60 opening being closed when the engine throttle is either fully open or closed, and opened only when the engine throttle is in an intermediate position between fully open and closed, 65 at which time the piston will float, the engine

suction operating against the stress of the spring.

While the preferred form of the invention has been herein shown and described, it is to be understood that various changes may be 70 made in the details of construction and in the combination and arrangement of the several parts, within the scope of the claims, without departing from the spirit of this invention.

75 What is claimed as new is:—

1. In combination, a carbureting chamber having a fuel nozzle and an air supply for atomizing fuel from the nozzle into the chamber, means responsive in its operation to the drop in engine suction for displacing a portion of the fuel from the supply and causing the same to augment the normal supply of fuel from the nozzle, and means controlled by the operation of the last said means for causing an additional supply of air to be directed into said chamber, the second recited means being rendered inactive when the engine throttle is wide open or closed.

80 2. In combination, a carbureting chamber having a fuel nozzle and an air supply for atomizing fuel from the nozzle into the chamber, means responsive in its operation to the drop in engine suction for displacing a portion of the fuel from the supply and causing the same to augment the normal supply of fuel from the nozzle, and means controlled by the operation of the last said means for causing an additional supply of air to be directed 85 into said chamber, the second said means being rendered inactive when the engine throttle is full open or closed, the last said means embodying a piston influenced by engine suction and a cylinder in which said piston operates.

90 3. In combination, a carbureting chamber having a fuel nozzle and an air supply for atomizing fuel from the nozzle into said chamber, means whereby upon a drop in engine suction, fuel will be forced through and ejected from said nozzle, and means whereby upon the operation of the first said means an additional supply of air will be directed into the fuel mixture independently with respect to the said nozzle, the second recited means being rendered inactive when the engine 95 throttle is full open or closed.

100 4. In combination, a carbureting chamber having a fuel nozzle and an air supply for atomizing fuel from the nozzle into said chamber, means whereby upon a drop in engine suction, fuel will be forced through and ejected from said nozzle, and means whereby upon the operation of the first said means an additional supply of air will be directed into the fuel mixture independently with respect to the said nozzle, the second recited means being rendered inactive when the engine 110 throttle is full open or closed, the last said means embodying a piston influenced in its 115

120

125

130

operation by engine suction, a cylinder in which the piston acts and an additional air supply opening or passage which is opened and closed by the operation of said piston.

- 5 5. In combination, a carbureting chamber having a fuel nozzle and an air supply, a throttle controlling the outlet from said chamber, means for controlling the fuel supply, said means being governed by the suction on the engine side of the throttle, an additional air supply passage, and means governed by the suction on the engine side of the throttle for normally closing said additional air passage, the last said air passage
- 10 15 when opened operating to admit an additional supply of air to be mixed with the fuel, said additional air passage being closed when the engine throttle is full open or closed.

6. In a carburetor, a carbureting chamber having a fuel nozzle and an air supply, a throttle controlling the outlet from said chamber, means for controlling the fuel supply, said means being governed by the suction on the engine side of the throttle, an air passage separate from the first said air supply for supplying additional air to the said chamber to mix with the fuel therein, a piston for closing and opening the said air pas-

sage, a cylinder in which the piston operates, means tending normally to move the piston in one direction, and means whereby engine suction will move the piston in the opposite direction and against the stress of the last said means, the said air passage being closed when the engine throttle is full open or closed.

7. In a carburetor, a carbureting chamber having a fuel nozzle and an air supply, a throttle controlling the outlet from said chamber, means for controlling the fuel supply, said means being governed by the suction on the engine side of the throttle, an air passage separate from the first said air supply for supplying additional air to the said chamber to mix with the fuel therein, a piston for closing and opening the said air passage, a cylinder in which the piston operates, means tending normally to move the piston in one direction, means whereby engine suction will move the piston in the opposite direction and against the stress of the last said means, and means whereby when the piston operates in one direction an additional supply of fuel will be delivered to said nozzle, the said air passage being closed when the engine throttle is full open or closed.
